AUTOMOBILE FLOOR MAT

Ben Ross Jackler, Beverly Hills, Calif.

Application August 18, 1953, Serial No. 26,498

Term of patent 14 years

(Cl. D9--6)

To all whom it may concern:

Be it known that I, Ben Ross Jackler, a citizen of the United States, residing at Beverly Hills, in the county of Los Angeles, State of California, have invented a new, original, and ornamental Design for an Automobile Floor Mat, of which the following is a specification, reference being had to the accompanying drawing, forming a part thereof:

Fig. 1 is a plan view of an automobile floor mat embodying my new design;

Fig. 2 is a detail fragmentary plan view of the shield portion thereof;

Fig. 3 is a detail fragmentary plan view of a corner portion thereof;

Fig. 4 is a fragmentary longitudinal sectional view thereof taken on the line 4—4 of Fig. 3;

Fig. 5 is a fragmentary transverse sectional view thereof taken on the line 5—5 of Fig. 3;

Fig. 6 is a fragmentary longitudinal sectional view through the central portion of the mat; and

Fig. 7 is a fragmentary inverted plan view of a corner portion of the mat.

The entire rear surface of the mat has the body pattern and margin shown in Fig. 7.

I claim:

The ornamental design for an automobile floor mat, as shown and described.
